UNITED STATES PATENT OFFICE.

KARL WIESER, OF BREDENEY, GERMANY, ASSIGNOR TO FRIED. KRUPP AKTIEN-
GESELLSCHAFT, OF ESSEN-ON-THE-RUHR, GERMANY.

PROJECTILE.

1,003,079.

Specification of Letters Patent. Patented Sept. 12, 1911.

Application filed October 10, 1910. Serial No. 586,274.

To all whom it may concern:

Be it known that I, KARL WIESER, a subject of the Emperor of Germany, and a resident of Bredeney, Germany, have invented 5 certain new and useful Improvements in Projectiles, of which the following is a specification.

In United States Patent No. 932,214 dated August 24, 1909, a projectile is disclosed 10 which is intended to be used with a gun or other projecting device having a bore for receiving the guiding-shaft of the projectile, and which projectile possesses a weight designed to slide on this shaft. On the shaft 15 there is provided a striking part which limits the rearward movement of the weight relative to the body of the projectile and effects the separation of the projectile from the shaft. The part of the shaft on which 20 the weight is made to slide is, for this purpose, supplied with ribs and the weight with corresponding grooves. The process of making these ribs and grooves is, however, tedious and expensive. The present invention 25 aims therefore at the simplifying of this shaft and weight.

The object is, in the present invention, reached by giving the part of the shaft whereon the weight slides, a smaller diameter 30 than that of the bore in the gun; and by supplying the shaft with an abutment or stop at the rear end of this small diameter, which stop will conform with the diameter of the bore in the gun. And the smaller 35 part of the shaft passes through a hole of the same diameter in the weight, so that, with the assistance of centering-faces on the weight and on the gun, the former will be in such a position, that its axis will coincide 40 with that of the bore of the gun.

One way of carrying out the object of the invention is shown in the accompanying drawing, wherein the projecting device consists of an ordinary gun and where the projectile is drawn in side view, partly in section; and the gun in longitudinal section outlined in dot and dash.

The body of the projectile is indicated by the letter A, its guide-shaft D, its sliding 50 weight K and the gun barrel C, the bore of which is intended for supporting the shaft D. The part of the shaft, along which the weight K is made to slide, is a smooth cylinder d^s , protruding through a suitable bore 55 k^s of the weight K, and having a smaller

diameter than the bore of the gun barrel. At its rear end the shaft D is provided with a stop or abutment d^s , which, as well as the shaft part d^s , is cylindrical, said stop d^s has a diameter corresponding to the caliber of 60 the gun and forms a striking head which limits the rearward movement of the weight K relative to the body of the projectile A. The gun has at the muzzle an outer cylindrical centering-face c^1 . This face c^1 of the 65 gun barrel fits into a suitably shaped recess in the weight K, in such a manner as to provide a centering device for the shaft and projectile with respect to the gun barrel. The centering surface k^s of the weight K is 70 coaxial with the bore k^s so that enough friction is obtained between the weight and the gun, when the former has been pushed over the muzzle-surface c^1 , to prevent the weight being torn off the gun by the friction 75 forces occurring in the bore k^s from the sliding of the shaft D.

Before the firing of the gun, the several parts of the projectile will be in the position shown in the drawing. The projectile is 80 then guided partly by the shaft-shank d^s in the bore k^s of the weight K which is connected with the gun barrel; and partly by means of the stop d^s in the bore of the gun-barrel C. This guiding is equally as accurate as the one obtained by the ribs provided on the shaft of the projectile referred to in the beginning of this specification and it is further accomplished with considerably 85 simpler means.

When the gun is fired, the shaft D will be driven out of the barrel, while the weight K remains on the gun until it is hit by the stop d^s of the shaft. By the blow hereby produced, the weight, on the one hand, will be 90 released from the gun barrel, and the movement of the shaft D, on the other hand will be so much retarded, that the shaft will be separated from the body of the projectile 95 shortly after the firing of the gun.

What is claimed is:—

1. A projectile having a projectile body, a shaft for guiding the projectile in the gun or projecting device, said shaft having its entire cross-sectional area less than the diameter of the bore, a stop formed with the shaft of substantially the diameter of the bore, driving and non-restraining connection between the shaft and the projecting device, a weight loosely mounted on the 105 110

shaft adapted to fit over the muzzle of the gun barrel to coöperate with the stop and effect the release of the shaft from the projectile body upon firing.

5. 2. The combination with a gun barrel, of a projectile having a projectile body, a cylindrical recess radially therein a weight constructed to fit over the muzzle of the gun barrel, a cylindrical aperture centrally of 10 the weight, a shaft having a cross-sectional area at one extremity of substantially the diameter of the bore, a reduced diameter adjacent thereto conforming to the cylindrical aperture in the weight, a reduced diameter 15 adjacent thereto conforming to the cylindrical recess in the projectile, and operable to effect separation between said projectile body and the shaft upon firing.
3. The combination with a gun barrel having a bore, of a projectile having a projectile body, a cylindrical recess formed radially therein, a weight provided with a central cylindrical aperture adapted to fit over the muzzle of the gun barrel, a shaft for guiding 20 the projectile in the gun barrel bore having three diameters successively reduced and adapted to fit the gun bore, the weight and the cylindrical recess respectively and operable to effect separation between said 25 projectile body and the shaft upon firing.

4. The combination with a gun barrel having a bore, of a projectile having a projectile-body, a shaft for guiding the projectile in the gun barrel bore, said shaft having a 30 portion of its length with its entire cross

sectional area less than the diameter of the bore, and another portion of its length of substantially the diameter of the bore and providing a stop, and a weight loosely mounted on the reduced portion of the shaft 40 and constructed to fit over the muzzle of the gun barrel and adapted to coöperate with the stop and effect the release of the shaft from the projectile-body upon firing.

5. The combination with a gun-barrel 45 having a bore, of a projectile having a projectile-body, a shaft for guiding the projectile in the gun-barrel bore, said shaft having a portion of its length of less diameter than the diameter of the bore, and another portion of its length of substantially the diameter of the bore and providing a stop, a weight loosely mounted on the reduced portion of the shaft and constructed to fit over and have frictional engagement with the 50 muzzle of the gun barrel; said engagement and the enlarged portion of the shaft providing a centering device for the projectile-body and shaft with respect to the axis of the gun-barrel bore, and effecting the release 55 of the shaft from the projectile body upon firing.

The foregoing specification signed at Bar-
men, Germany, this 20th day of September,
1910.

KARL WIESER. [L. S.]

In presence of—

ALFRED HENKEL,
WALTER VONNEGUT.
